(57) **CLAIM**

The ornamental design for a sponge container as shown and described.

DESCRIPTION

FIG. 1 is a side elevational view the sponge container showing my new design;

FIG. 2 represents a front elevational view of the sponge container showing my design which is the same as the rear view of my new design;

FIG. 3 is a top view thereof; and,

FIG. 4 is a bottom view thereof.

The broken lines depict portions of the article that form no part of the claimed design.

1 Claim, 2 Drawing Sheets
